[57] **CLAIM**

The ornamental design for a universal end cap for a movable wall panel, substantially as shown and described.

DESCRIPTION

FIG. 1 is a top plan view of a universal end cap for a movable wall panel embodying our design;

FIG. 2 is a front elevational view thereof;

FIG. 3 is an elevational view as seen from either side thereof;

FIG. 4 is a rear elevational view thereof;

FIG. 5 is a sectional view taken along the line 5—5 of FIG. 2;

FIG. 6 is a bottom plan view thereof;

FIG. 7 is an isometric view as seen from the front; and

FIG. 8 is an isometric view as seen from the rear.
